Specification for Design.

Patented Nov. 11, 1919.

Application filed June 3, 1919. Serial No. 301,586. Term of patent 7 years.

To all whom it may concern:

Be it known that I, ROSE C. HAMILL, a citizen of the United States, residing at Oakland, in the county of Garrett and State of Maryland, have invented a new, original, and ornamental Design for a Combination Cake Mixer, Beater, Turner, Lifter, and Measuring-Spoon, of which the following is a specification, reference being had to the accompanying drawing, forming a part thereof.

Figure 1 is a plan view of the combination cake mixer, beater, turner, lifter, and measuring spoon showing my new design.

Fig. 2 is a side elevation of the same.

I claim:

The ornamental design for a combination cake mixer, beater, turner, lifter, and measuring spoon, as shown.

ROSE C. HAMILL.
